UNITED STATES PATENT OFFICE.

WILLIAM A. ROBBINS, OF PORTLAND, OREGON.

SLEEPING-CAR.

1,232,720.

Specification of Letters Patent. Patented July 10, 1917.

Application filed October 7, 1915. Serial No. 54,549.

To all whom it may concern:

Be it known that I, WILLIM A ROBBINS, a citizen of the United States, residing in the city of Portland, county of Multnomah, 5 and State of Oregon, have invented certain new and useful Improvements in Sleeping-Cars, of which the following is a specification.

My invention relates to sleeping cars, and 10 has as its principal object to provide in a sleeping car a new and novel arrangement of the berths, whereby each berth has a greater vertical dimension for all, or at least a portion, of its length, thus making it possible 15 for the occupant to sit upright therein, with ample clearance for his head. In order to do this, I arrange the berths in staggered, or overlapping, relationship longitudinally of each other, having an upper, or intermediate, berth arranged somewhat lower, when made up, than the present upper berths, and each overlapping the adjacent ends of the two lower berths thereunder. For example, the lower berth would be made 20 up in the usual manner, as with the present modern equipment. An upper berth, instead of being directly above the lower berth for its full length, would be made up with its middle portion supported above the back of 25 the seat, and its opposite ends overlapping the adjacent ends of the two lower berths thereunder. This would give an L-shape berth space under both ends of the upper berth, the taller portion of which extends 30 upwardly past the opposite ends of the berth above. This, of course, necessitates that one of each pair of adjacent lower berths must be made up with the head in the opposite direction, or, in other words, the persons 35 occupying the two adjacent lower berths would lie with their feet toward each other. As it is not uncommon for persons to have their berths made up with their heads in the opposite direction to that which is most 40 common, this will be no serious objection, and will be more than overcome by the fact that the person can sit upright in his berth. The berth immediately above the seat, I lower somewhat when it is made up by providing 45 it with a double hinge connection with the side of the car, whereby its hinged side, when made up, drops down a distance below the position it occupies when closed up; thus this upper berth is made easy of 50 access and has the benefit of the upper halves of two windows, with a great deal of clear-

ance above, so that the occupant can sit upright, or even stand upright therein.

A most important feature, made possible by my improved arrangement, is the improved ventilation of both lower and upper berths. This is due, not only to the increased space, but to window service in both berths.

In order that others may clearly understand my invention, I have illustrated in the accompanying sheet of drawings one practical embodiment thereof, which I will now describe.

Figure 1 is a side elevation of a modern 70 sleeping car with a portion broken out, showing the car in longitudinal section through the aisle, in order to show my improved arrangement of sleeping berths, the arrangement of the seats and berths at opposite sides of the aisle being the same.

Fig. 2 is a vertical cross sectional view thereof, showing one of the upper berths made up, and showing one in its up position in solid lines, and in down position in 80 dotted lines;

Fig. 3 is a fragmentary cross sectional view, on a larger scale, showing an upper berth made up in position for use in full lines, and in raised position in dotted lines, 85 showing a hinge connection which makes possible the lowering of the berth to a point below the position occupied under present construction; and

Fig. 4 is a fragmentary longitudinal vertical sectional view through the aisle of a car, showing a slightly modified arrangement with a third or high berth arranged between each pair of upper berths.

Referring now more in detail to the drawings, 1-1 indicate the ends of the ordinary Pullman double seats, and 2-2, the lower berths as made up between the seats. 3-3 designate what I will term intermediate berths, made up ready for use and, as 100 shown, resting down upon the top of the back of the seat immediately thereunder, in the manner indicated in Figs. 1 and 4. Referring to Figs. 2 and 3, it will be noticed that the berth 3, is hinged at its back edge 105 to the wall by means of a double hinge member 4, adapted to swing downwardly, as shown in full lines in Fig. 3, when the berth is let down for use, and to be swung upwardly with the body of the berth, as indicated in dotted lines, when the berth is 110 in its raised position. The usual support-

ing chain, or cable, 5, is attached to the outer edge of the berth, as clearly shown in Figs. 2 and 3, and I have also provided at the rear edge of each such berth, a supporting cable, or chain, 6, adapted to be automatically wound up as the berth is raised, by means of a spring-actuated drum, at 7. Every other intermediate berth can be arranged in this manner, thus giving ample head room in the lower berths, at opposite ends of the intermediate berth there above.

In order to utilize the upper space above alternate seats, and directly over which there is no berth, I have provided a slightly modified arrangement by constructing a high berth, as 8, Fig. 4, which may be hinged to the side of the car in the usual manner at a point above the windows and still leave ample head room in the lower berths thereunder. When folded up these high berths would appear as 8, Fig. 1, similar to the intermediate berths 3, when they are closed up, as shown at the right hand end of Fig. 1, at the broken line. In fact this high berth would be about the same as are the present upper berths, while the intermediate berth would be just as desirable, if not more so, as is the present lower berth, because it can be let down to a convenient position upon the back of the seat of the present car construction, and also because each intermediate berth would have the benefit of portions of two car windows, whereas the present upper berth has no window service at all.

Referring to the left hand end of Fig. 1, it will be noticed that the intermediate berth 3^a, for a portion of its length, extends into a recess formed by taking in a portion of the wash room. A panel 9, covers half of the front of the berth space, while the space below said intermediate berth 3^a, and back of the first seat 1^a, is used as a closet 10, for linen and the like.

The berths would be closed off from each other by means of suitable removable partition members, as 11—11 and 12—12, the partition members 11 being adapted to be inserted at the ends of berths 3 and 3^a, while the partition members 12, would be inserted between the lower berths and immediately over the alternate seat backs where there is no intermediate berth, as clearly indicated in Fig. 1. Where a high berth construction is used, the partition members 11 would be used at the ends of the intermediate berths and a partition member 13 would be used immediately above the seat back and underneath the body of said high berth, as illustrated in Fig. 4.

Thus I have provided lower berths with ample head room and one full window and one-half window, making them more desirable, because much more convenient, than the present lower berths, and I have also

provided intermediate berths which are easy of access from a small stool, or step, and which have window service and lots of room for the occupant, thus giving perfect ventilation, and I have also made provision for high berths, which are substantially the same as are the present upper berths. It will be noted that an intermediate berth can only be provided over every alternate seat, and if the high berth arrangement is used, the high berths would occupy the spaces above the remaining alternate seats, and at a higher location than the down position of the intermediate berths.

When the intermediate and high berths are all closed up, they occupy the same elevation and give a uniform panel appearance, similar to present arrangement.

I am aware that changes in the details of construction and arrangement, as here shown for illustrative purposes, can be made without departing from the spirit of my invention, and I do not, therefore, limit the invention, except as I may be limited by the hereto appended claims.

I claim:

1. In a sleeping car, a series of seats, arranged in pairs back to back crosswise of the car, a berth hingedly attached at one side to the side of the car above each alternate pair of seats and adapted to be let down with its middle portion above the back of said seats, substantially as and for the purpose described.

2. In a sleeping car, in combination with a series of seats arranged back to back in the usual manner, a series of upper berths hingedly secured to the side of the car above alternate seats, and adapted to be let down with their middle under side portions over the backs of said seats, each of said upper berths projecting at its opposite ends over the seats arranged back to back thereunder, substantially as described.

3. In a sleeping car, a series of seats arranged in pairs back to back, a berth hingedly secured at its side to the side of the car with double hinge members, whereby the back edge of said berth can be swung from a point above the point of attachment to the side of the car to a point below said point of attachment, said berth being adapted to be let down with its middle portion above the backs of said seats, whereby its opposite ends project over the two seats arranged back to back, substantially as described.

4. In a sleeping car, in combination with a series of double seats arranged back to back, a series of intermediate berths hingedly secured to the side of the car at their outer edges and arranged one above each alternate seat back and adapted to be lowered with its middle portion above said seat back, and a series of high berths hinged to the side of the car and arranged above the

other alternate seat backs and between said intermediate berths, and partition members adapted to be inserted at the opposite ends of each berth.

5. In a sleeping car, in combination with a series of double seats arranged back to back, a series of upper berth bodies hingedly secured to the side of the car by a double hinge mechanism, whereby the hinged edge 10 of said berth body can be lowered bodily from an upper to a lower position, as said berth body is let down for use, means for supporting said berth bodies in raised and lowered positions, said berth bodies being 15 arranged above alternate double seats, an upper berth positioned above the back of each of the other alternate seats, whereby to overlap at its opposite ends the seat portions of said double seats thereunder, and 20 partition members adapted to be inserted at the opposite ends of each of said upper berths and at the opposite ends of the berths thereunder, substantially as described.

6. In a sleeping car, a series of lower 25 berths arranged longitudinally of the car, a series of upper berths hingedly secured at their sides to the side of the car and adapted to be swung upwardly and arranged longitudinally of the car above said lower 30 berths in staggered relationship therewith, whereby the opposite ends of an upper berth when let down overlap the adjacent ends of two lower berths, substantially as described.

7. In a sleeping car, a series of lower 35 berths arranged longitudinally of the car, a series of upper berths arranged longitudinally of the car above the adjacent ends of alternate pairs of lower berths, whereby the

opposite ends of an upper berth overlie the adjacent ends of two lower berths, and a 40 series of high berths arranged longitudinally of the car above the adjacent ends of the other alternate lower berths, substantially as described.

8. In a sleeping car of the character referred to, in combination with a double seat, the seat portions of which are arranged back to back, a berth structure hingedly secured to the side of the car, longitudinally of the car, and adapted to be let down so that its 45 middle portion rests directly above the back of said seat, its opposite ends projecting over and above the seat portions of said double seat, substantially as shown and described.

9. In a sleeping car of the character referred to, in combination therewith, a series of double seats arranged transversely of the car at each side of a middle aisle, each of said double seats having a common back, 60 berth structures hingedly secured to the sides of the car, and extending longitudinally thereof, above alternate double seats, each of said berth structures being adapted to be let down into position for use with its 65 middle portion directly above the common back of the double seat thereunder, with its opposite ends projecting over and above the seat portions thereof, substantially as and for the purpose described.

Signed at Portland, Multnomah county, 70 Oregon, this 1st day of October, 1915.

WILLIAM A. ROBBINS.
